US00D758744S

(12) **United States Design Patent**
Blakely et al.(10) **Patent No.:** **US D758,744 S**
(45) **Date of Patent:** **** Jun. 14, 2016**(54) **UPPER BODY GARMENT WITH OUTER SURFACE ORNAMENTATION**(71) Applicant: **Under Armour, Inc.**, Baltimore, MD (US)(72) Inventors: **Kyle Sanders Blakely**, Baltimore, MD (US); **Peter Fong**, Vancouver (CA); **Julian McClain**, Baltimore, MD (US)(73) Assignee: **Under Armour, Inc.**, Baltimore, MD (US)(**) Term: **14 Years**(21) Appl. No.: **29/490,376**(22) Filed: **May 9, 2014****Related U.S. Application Data**

(60) Division of application No. 29/448,227, filed on Mar. 11, 2013, now Pat. No. Des. 704,455, and a continuation of application No. 13/618,835, filed on Sep. 14, 2012.

(51) **LOC (10) Cl.** ..... **05-05**(52) **U.S. Cl.**USPC ..... **D5/56**; D2/840(58) **Field of Classification Search**

Primary Examiner — Karen S Acker(74) *Attorney, Agent, or Firm* — Maginot, Moore & Beck LLP**CLAIM**

The ornamental design for an upper body garment with outer surface ornamentation, as shown and described.

DESCRIPTION

The sole FIGURE is a plan view of an upper body garment with outer surface ornamentation showing our new design. The broken lines surrounding the fabric with surface ornamentation in the sole figure represent the boundaries of the claim and form no part thereof.
